APPARATUS FOR RAISING LIQUIDS

Pearl C. Norman and Kenneth C. Norman,
Oklahoma City, Okla., assignors to Phillips
Petroleum Company, a corporation of Delaware

Application January 13, 1938, Serial No. 185,314

3 Claims. (Cl. 103—10)

This invention relates to submersible pumps and gas lift producing operations in the method of raising liquids from underground wells.

In producing liquids from underground wells, particularly in the producing of oil wells, the submersible electrical centrifugal pump has played a very important part since its perfection. The pump is lowered within the casing until it is immersed within the liquid. A conductor of electricity goes from the ground surface to the pump in the well hole bottom to supply current to the pump motor and the liquid is forced to the surface of the ground through a tubing string connected to the pump outlet and within the casing.

This type pump gives very efficient and economical operation. The pump will operate at a constant high speed and the size of the pump will be determined by the quantity of fluid and 20 the height it is to be lifted. If it should occur that the well starts producing water along with the oil or the volume should be increased for any purpose, it may be economically unsound to continue operating the submersible pump or to 25 replace it with a larger sized pump.

By this invention it has been found economically possible to continue operation of the pump when the well starts producing water in great quantities with the oil or to increase the volume 30 of liquid from the well for any purpose. By the means here disclosed, the production from the well is increased by using the pump to force the liquid half way up the tubing column and by gas lifting the liquid the remaining distance to 35 the surface of the ground. Since the pump was designed to force a certain quantity to the ground surface, now that it is only required to force it half way, half the load is taken off the pump which in turn will increase the amount of liquid 40 it will deliver to the half way point in the tubing string. The equipment has thus been made to handle a greater quantity of liquid without the expense of pulling the tubing and pump from the well to place a larger pump in the well 45 hole.

While the submersible electrical centrifugal pump has been used as an example in this discussion, it is to be understood the invention is not limited to this type pump but may be employed with any submersible pumping unit. It is also to be noted that a change can be made from combination pumping and gas lift back to straight pumping without the necessity of pulling the tubing and pump from the well.

50 It is an object of this invention to provide

means for raising liquids from an underground well.

It is a further object of this invention to provide a means whereby the producing operation of an underground well may be changed from one of straight pumping to one of combination pumping and gas lift or vice versa.

It is a still further object of this invention to provide a means whereby the producing operation of an underground well may be changed 10 from one of straight pumping to one of combination pumping and gas lift or vice versa, without the necessity of pulling the tubing and pump from the well.

It is a still further object of this invention to provide a means whereby the producing operation of an underground well may be changed 15 from one of straight pumping to one of combination pumping and gas lift or vice versa without the necessity of pulling the tubing and pump 20 from the well.

Other objects and advantages of the invention will be apparent during the course of the following description.

In the accompanying drawing, forming a part 25 of this specification, and in which like numerals are employed to designate like parts throughout the same:

Fig. 1 is a diagrammatical view of a well hole showing the pump in the well and the sliding 30 sleeve means half way up the tubing,

Fig. 2 is an enlarged fragmentary longitudinal sectional view of the sliding sleeve in the tubing with the pumping unit forcing the liquid 35 to the surface of the ground,

Fig. 3 is an enlarged fragmentary longitudinal sectional view of the sliding sleeve in the tubing with the pumping unit forcing the liquid half way up the tubing and gas lifting the remaining distance.

In the drawing, wherein for the purpose of illustration is shown a preferred embodiment of my invention, the numeral 1 designates the bottom of the well with the well being lined by casing 2. Mounted within the casing 2 and attached to the tubing 4 is any type of submersible pump 3 for forcing the liquid from the well into the tubing 4 from where it is delivered to the surface of the ground through the tubing 4. Half way up from the bottom of the well is placed a conventional packer 5 between the casing and the tubing. Having thus packed off between the tubing 4 and casing 2, there is a space 6 which provides a conduit from the packer to the surface of the ground connecting with the dis- 50 55

charge pipe 7. Above the packer 5 and within the tubing 4 is mounted the sliding sleeve mechanism 8 which functions to change the producing method from one of straight pumping to one of combination pumping and gas lift, better shown in both Figures 2 and 3.

The sleeve mechanism 8 comprises an outer section of tubing 9 which has stop shoulders 10 and 11 at the top and bottom thereof. The tubing 9 forms a section of the tubing string 4 and has screw threads at the upper end to receive the next section of tubing above it and the lower end has screw threads 13 which screw thread into the packer 5 with the lower section of tubing also threading into the packer. The tubing section also has spaced openings 14 and 15 through the wall thereof which communicate with the annular space 6.

Mounted to have a sliding fit within the tubing section 9 is the sleeve 16 having piston rings 17 to insure a tight fit with the inner wall of the tubing section 9. The travel of the sleeve is limited by the stop shoulders 10 and 11 in its movement in the tubing section. A spring 18 in the lower portion of the tubing section 9, keeps the sleeve in its upper position against the stop shoulder 11. The lower end of the spring 18 may be supported by a shoulder formed in the section 8 or a pin may extend across the section to support the same. Mounted within the sliding sleeve 16 is a ball check valve 19 which allows flow from the bottom of the hole, being lifted from the seat by the pressure of the liquid, but upon pressure being exerted on the ball 19 from above, the ball will seat and not allow any flow downwardly. Openings 20 and 21 are drilled through the wall of the sliding sleeve 16 with one opening above and the other below the check valve 19.

In the operation of the device, Fig. 2 shows the arrangement of parts when the pump at the bottom of the well is being used to force the liquid from the well to the surface of the ground. It will be seen that the spring 18 forces the sleeve upwardly against the stop shoulder 11, which in turn keeps the openings 14-20 and 15-21 out of alignment. The pressure of the liquid will lift the ball 19 from the seat and allow the liquid to pass on to the surface of the ground through the tubing 4.

Fig. 3 shows the operation of the sleeve when it has become necessary to change from straight pumping to combination gas lift and pumping. The pump is shut down, and gas under pressure is turned down the inner tubing 4. The pressure of the gas will force the ball valve to seat and the pressure will build up back of the sliding sleeve member, thus forcing the sleeve 16 downwardly against the spring until the sleeve seats on the shoulder 10. With the sleeve in this position, the ports 14-20 and 15-21 will align and connect the interior of the tubing 4 with the annular space 6. The liquid being forced from the well by the pump will enter the annular space 6 through the ports 15 and 21. The gas will be under a much greater pressure than the liquid coming from the well and will thus function to hold the check valve on the seat, and force the oil to enter the annular space through the openings 15 and 21. The gas under pressure will enter the annular space 6 through the openings 14

and 20 and will lift the oil the remaining distance to the surface of the ground. If it is desired to change back to straight pumping, the only change necessary is to close off the gas under pressure down the inner tubing and the tension of the spring 18 will close the sleeve and the device is again ready to operate as a straight pumping unit.

It is to be understood that the form of this invention, herewith shown and described, is to be taken as a preferred example of the same, and that various changes in shape, size and arrangement of parts may be resorted to, without departing from the spirit of the invention or the scope of the subjoined claims.

Having thus described our invention, we claim:

1. The combination for producing a well comprising a pump in the well hole with the well being cased, tubing within the casing and connecting the pump with the surface of the ground, a sliding sleeve located in a tubing section at a point below the surface of the ground, a packer between the casing and tubing below the sliding sleeve, a check valve in said sleeve which allows liquid to pass upwardly through the sleeve but closes with downward pressure and said sleeve being actuated by gas under pressure, openings in the tubing section communicating with the space between the casing and tubing above the packer and openings in the sleeve which align with the openings in the tubing section when the sleeve is forced downwardly by gas under pressure from the surface of the ground.

2. The combination for producing a well comprising a pump in the well hole with the well being cased, tubing within the casing and connecting the pump with the surface of the ground, a sliding sleeve located in a tubing section at a point below the surface of the ground, a packer between the casing and tubing below the sliding sleeve, a check valve in said sleeve which allows liquid to pass upwardly through the sleeve but closes with downward pressure, a passage in the sleeve below the check valve, a like passage in the tubing, said sleeve being forced downwardly by gas under pressure from the surface of the ground to bring the passages in the sleeve and tubing into alignment and connect the tubing below the check valve with the annular space between the tubing and casing.

3. The combination for producing a well comprising a pump in the well hole with the well being cased, tubing within the casing and connecting the pump with the surface of the ground, a sliding sleeve located in a tubing section at a point below the surface of the ground, a packer between the casing and tubing below the sliding sleeve, a check valve in said sleeve which allows liquid to pass upwardly through the sleeve but closes with downward pressure, passages in the sleeve above and below the check valve, like passages in the tubing, said sleeve being forced downwardly by gas under pressure from the surface of the ground to bring the passages in the sleeve and tubing into alignment and connect the tubing above and below the check valve with the annular space between the tubing and casing.
